UNITED STATES PATENT OFFICE.

RAYMOND A. HEISING, OF EAST ORANGE, NEW JERSEY, ASSIGNOR TO WESTERN ELECTRIC COMPANY, INCORPORATED, OF NEW YORK, N. Y., A CORPORATION OF NEW YORK.

RADIO TRANSMISSION SYSTEM.

Application filed October 1, 1919. Serial No. 327,744.

To all whom it may concern:

Be it known that I, RAYMOND A. HEISING, a citizen of the United States, residing at East Orange, in the county of Essex, 5 State of New Jersey, have invented certain new and useful Improvements in Radio Transmission Systems, of which the following is a full, clear, concise, and exact description.

10 This invention relates to radio transmission systems and more particularly to duplex radio communication systems.

The general object of the invention is to provide improved means of and methods 15 for duplex radio transmission.

A particular object is to provide a system wherein transmission can be carried on at one wave length and reception at another wave length, choice of several wave 20 lengths being available for reception irrespective of which wave length is being used for transmission and vice versa.

A further object is to provide a system 25 which can be so balanced that transmission and reception can be carried on at a variety of combinations of wave lengths without readjusting the balance.

A further object is to provide efficient 30 and practical means whereby the transmitting and receiving wave lengths may be independently changed.

A further object is to provide a novel 35 form of network for balancing the impedance of an antenna particularly for balancing the antenna at several wave lengths.

Additional objects of the invention will 40 be apparent to those skilled in the art from a perusal of the following detailed description.

45 Fig. 1 of the accompanying drawings is a diagrammatic representation of a system embodying the invention, Figs. 2 and 2^a are diagrams hereinafter referred to in connection with the explanation of the duplex balance of the system; and Fig. 3 shows a preferred manner of winding the antenna coil.

50 Fig. 1 illustrates a station of a duplex radio system wherein a radiating conductor 1 is connected to ground through a coil 2 and a balancing network N. A condenser may in some instances be included in series with the conductor 1 to increase the capacitive reactance thereof. A variable capacity

4 is shunted around the coil 2 for a reason 55 hereinafter stated. The coil 2 is wound in a particular manner hereinafter described. The conductor 5 contains or is suitably associated with a source of signaling waves to be transmitted. In the present instance 60 this source is the means connected with the coil 6 in which is induced an electromotive force corresponding to a high frequency wave modulated in accordance with speech waves. A condenser 7 may be provided to 65 give the conductor 5 a desired reactance. The means for inducing suitable electromotive forces in coil 6 comprises any suitable system S which in the present instance 70 consists of a high frequency oscillator O of the thermionic type. Oscillator O comprises a vacuum tube 8 having in its grid circuit a coil 9 coupled to coil 6 and blocking condenser 10, the coil 9 and condenser 10 being shunted by a resistance 75 leak path 11. The plate circuit of tube 8 includes condenser 12 in series with the parallel arrangement of coil 13 and the variable condenser 14, the coil 13 being coupled to coil 6. The function of the condenser 80 14 is to vary the effective coupling of the coil 13 to the coil 6. Coils 9 and 13 are so arranged that the direct mutual inductance therebetween is negligible. The anode-cathode current of tube 8 is provided from 85 source 15 through the speech frequency choke coil 16. Shunted around tube 8 is the anode-cathode path 17 of tube 18. The impedance of tube 18 is varied in accordance 90 with speech waves by providing a circuit 19 in which speech frequency waves are produced and coupling the circuit 19 to the input circuit 20 of the tube 18 by the speech frequency transformer 21. Between the negative terminal of the source 15 and the 95 cathodes 22 of the tubes 8 and 18 is connected a resistance 23 and a condenser 24 in shunt thereto. The total space current for tubes 8 and 18 passes through resistance 23, hence by connecting the grid element 25 of tube 18 to the negative terminal of resistance 23, the grid 25 is maintained at a suitable negative potential with respect to its cooperating cathode. The resistance 23 may be of any value which will give the 100 most efficient operation. Condenser 24 is of sufficient capacity to be of low impedance to such fluctuating potentials as are

impressed across resistance 23. Since the total current through resistance 23 is approximately constant, the normal potential on grid 25 will be substantially constant.

The network or artificial antenna comprises a variable inductance in series with the combination of a variable resistance shunted by a variable inductance and also 10 in series with a variable condenser. This form of network is of peculiar utility in that it will not only balance the antenna for one wave length but may be adjusted to give 15 a very exact balance at two wave lengths and a fairly accurate balance over a considerable range of wave lengths. This is illustrated in Fig. 2, where the effective capacity of an ordinary type of antenna, plotted against wave length corresponds over a certain range of values to the curve "a", while 20 the effective capacity of a condenser having a small inductance in series similarly plotted corresponds to a curve having the form "n". By proper adjustment the two curves may 25 be made to cross each other at two selected wave lengths, for example, 190 and 315 meters. Then at other wave lengths such as 150, 230, 270 and 360 meters the unbalance will be comparatively slight. It is further 30 illustrated in Fig. 2^a where the effective resistance of an ordinary type of antenna plotted against wave length is represented by the curve "a" and the effective resistance of an inductance and resistance, such as 35 inductance 30 and resistance 31 in parallel, is shown by the curve "n". By properly choosing these values the two curves may be made to approximately coincide over a certain range of wave lengths, as, for example, 40 from 150 to 360 meters, which may be taken as the range over which operation is to be carried on. By combining this parallel combination with the condenser 32 and the inductance 33, as shown in Fig. 1, the 45 behavior of effective capacity and the effective resistance as a function of the wave length, as shown in Figs. 2 and 2^a, can be made to occur. The network contains four variables, and by properly adjusting them 50 the network can be made to give at the wave lengths represented by the points *b* and *c* the same effective capacity and the same effective resistance as occur in the real antenna. Over the desired operating range 55 the departure of the actual antenna effective capacity and resistance curves from those of the network will be so small as not to interfere seriously enough with the balance to cause trouble in operating the set. The 60 two points *b* and *c* corresponding to 190 and 315 meters respectively at which the most accurate balance occurs may in part, for instance by proper adjustment, be made to fall at such other wave lengths other 65 than 190 and 315 meters as may be desired.

The curves of Figs. 2 and 2^a are not drawn to exact scale but are merely intended to illustrate a general principle.

The coil 2 is wound on a suitable cylindrical core 26 as shown in Fig. 3. In passing 70 from the conductor 5 to the radiating member 1 the part 2' is traversed. In passing from conductor 5 to the network N, the part 2'' is traversed. Since these paths are in opposite directions, the reactance introduced 75 into the conductor 5 will be negligible if the coefficient of coupling between the parts of coil 2 is approximately unity. The coefficient of coupling between the two parts of the coil is caused to be approximately unity 80 by winding the parts 2' and 2'' with their turns closely adjacent. The operating requirement is that the total ampere turns of the parts of the coil be equal. This is most 85 simply accomplished by making the number of turns in the parts of the coil equal. Approximately one-half of the generated power is then wasted in the network N. For short range sets this is no serious difficulty. For higher power sets for long 90 range work, the coil 2 may be so designed and the network N so adjusted that a much smaller amount than one-half of the power is wasted in the network N. The impedance 95 of the network will then be proportionately high, care being taken to see that the power factor of the network is equal to that of the antenna.

The receiving set R comprises a tuned or 100 other suitable selective circuit 27 coupled to the coil 2 in such a manner that the minimum effect of the outgoing energy is impressed upon the circuit 27. This may be accomplished under ordinary circumstances 105 by giving coil 28 in circuit 27 a single adjustment in its spatial relation to coil 2 which will be suited for all combinations of wave lengths to be utilized. The circuit 27 comprises the input circuit of a detector D. An amplifier A is provided to amplify 110 the detected current and transfer the energy to any suitable signal indicating device 29. Suitable shielding is provided as shown in dotted lines so that capacity to ground variations will not disturb the balance.

In operation the coil 6 is varied to cause 115 the transmitted wave to be of a suitable length, this being determined in general by the natural frequency of the conductor 5 in series with the parallel branches comprising the antenna and the artificial antenna. The condenser 4 may be varied to tune the antenna for reception. The length 120 of the transmitted wave is wholly independent of the capacity of the condenser 4 since potentials impressed on conductor 5 will cause no difference of potential across the condenser 4, if the balance is exact, and only 125 a negligible difference of potential if the 130

- balance is slightly imperfect. Thus it is possible to transmit on any one of several wave lengths and have available any one of several wave lengths for reception. Either 5 the transmitting or the receiving wave length may be changed at any time. Transmission and reception may be carried on either simultaneously or successively and it is possible to receive from one station while 10 transmitting to one or more others.
- The novel features which are believed to be inherent in the invention are defined in the appended claims.
- What I claimed is:
- 15 1. A duplex radio station comprising a radiatory antenna and an artificial antenna for balancing said radiatory antenna, said artificial antenna comprising a capacity in series with a parallel arrangement of inductance and resistance.
2. An artificial antenna comprising a variable inductance in series with a variable capacity and the combination of a variable resistance in parallel with a second variable 25 inductance.
3. In a radio system, a radiating circuit, a balancing circuit therefor including an element having chiefly resistive impedance at radio frequencies, and an element shunted around said first named element having chiefly inductive impedance at radio frequencies.
- 30 4. A duplex radio system comprising an aerial, separate and independent tuning means for transmission and reception, and a network comprising impedance elements simulating the impedance of said aerial over a wide range of frequencies whereby, with a fixed and invariable adjustment of said elements, either the transmitting or receiving frequencies may be varied over a considerable frequency range by means of one of said tuning means, with a minimum of interference with the frequency established by the other tuning means.
- 45 5. A duplex radio station comprising a radiating member, a path from said member to ground through a closed circuit contain-
- ing an inductance and a capacity, and through an artificial antenna, and a branch 50 path to ground from an intermediate point on said inductance.
6. A duplex radio system comprising a transmitter and a receiver, a circuit for transmission and reception and a variable 55 tuning condenser for reception connected across points of said circuit across which said transmitter sets up only negligible differences of potential.
7. In a duplex radio system an aerial 60 member for radiating the outgoing and absorbing incoming wave energy, a balancing member for said aerial member, an inductance element connecting said balancing member with said aerial member, a connection from an intermediate portion of said element to ground through a path connected to transmitting means, a capacity for tuning received waves shunted around said element and a receiver coupled to said 70 element.
8. In a duplex radio system a generating system for producing waves and varying them in accordance with signals, a path connected to said system and connected to 75 the middle point of a divided impedance element, a receiver equally coupled to the parts of said divided impedance element, and tuning reactance means shunted around the impedance element for tuning for received waves.
9. In a duplex radio system a transmitting sources of waves, frequency varying means associated therewith, two paths to be traversed by waves from said source, said 85 paths being oppositely coupled to a receiver circuit, and tuning means for receiving connected across similar portions of said paths whereby the operation of said transmitting source at any frequency of waves to be 90 transmitted sets up only negligible differences of potential across said tuning means.

In witness whereof, I hereunto subscribe my name this 27th day of September, A. D., 1919.

RAYMOND A. HEISING.
